(57) **CLAIM**

The ornamental design for a Quick Coupling as shown and described.

DESCRIPTION

FIG. 1 is a front-right-top perspective view of the Quick Coupling showing my new design;

FIG. 2 is a front elevational view of the Quick Coupling of FIG. 1;

FIG. 3 is a rear elevational view of the Quick Coupling of FIG. 1;

FIG. 4 is a left side elevational view of the Quick Coupling of FIG. 1;

FIG. 5 is a right side elevational view of the Quick Coupling of FIG. 1;

FIG. 6 is a top plan view of the Quick Coupling of FIG. 1;

FIG. 7 is a bottom plan view of the Quick Coupling of FIG. 1;

FIG. 8 is a front-right-bottom perspective view of the Quick Coupling of FIG. 1;

FIG. 9 is a cross-sectional view of the Quick Coupling, taken from lines 9-9 in FIG. 6.

FIG. 10 is a front-right-top perspective view of a second embodiment of the Quick Coupling thereof.

FIG. 11 is a front elevational view of the Quick Coupling of FIG. 10;

FIG. 12 is a rear front elevational view of the Quick Coupling of FIG. 10;

FIG. 13 is a left side elevational view of the Quick Coupling of FIG. 10;

FIG. 14 is a right side elevational view of the Quick Coupling of FIG. 10;

FIG. 15 is a top plan view of the Quick Coupling of FIG. 10;

FIG. 16 is a bottom plan view of the Quick Coupling of FIG. 10;

FIG. 17 is a front-right-bottom perspective view of the Quick Coupling of FIG. 10; and,

FIG. 18 is a cross-sectional view taken from lines 18-18 in FIG. 15 of second embodiment.

1 Claim, 18 Drawing Sheets
